UNITED STATES PATENT OFFICE.

BENJAMIN E. FITCH, OF GREENWICH, CONNECTICUT.

APPARATUS FOR HANDLING FREIGHT.

Application filed September 30, 1924. Serial No. 740,794.

The employment of removable automobile bodies as containers for package freight permits the utilization of buildings, for storage and for rehandling for distribution, in localities where the expense of rail-track terminals would be prohibitive. Temporary storage of containers in such off-track buildings relieves the rail head terminal and also reduces the consignee's charges over those necessary in the usual system of breaking bulk and warehouse storing. To obtain the most advantageous locations for container storage at reasonable expense, it is frequently desirable to use facilities afforded by existing buildings, but the overall clearance between the floor and ceiling in many of these buildings precludes the use of individual crane trackways for handling heavy loaded bodies.

One of the objects of my invention therefore, is the provision of means for equipping buildings, particularly those having low clearance between the floor and ceiling, for storing removable automobile bodies, either while loaded or unloaded, and for enabling such bodies or containers to be shifted about in an expeditious manner to facilitate the movement of motor trucks which are employed for transporting containers to and from the building. In this connection, my invention contemplates an arrangement of apparatus which will minimize the necessity for expensive hoisting apparatus and elevator equipment.

I carry out the above objects by arranging a truck passageway into the building, providing an overhead trackway for supporting a traveling crane which is adapted to raise and transport removable automobile bodies or containers, and employing carriages which are adapted to travel beneath the trackway and are arranged to support a container independently of the crane. These carriages are positioned at the level of the corresponding floor in the building, wherefore a container may be readily transferred to a storage lane leading from the hoisting well.

One form of arrangement for carrying out my invention is hereinafter more fully set forth in the following description, which relates to the accompanying drawings, while the essential features are summarized in the claims.

In the drawings, Fig. 1 is a side elevation partly broken away of a warehouse wherein the lower two floors are equipped with my apparatus for container storage purposes; Fig. 2 is a similar side elevation of a portion of a two-story building embodying my invention of hoisting and transporting apparatus; Fig. 3 is an end elevation (with the wall and doors removed) of the building illustrated in Fig. 2; Fig. 4 is a sectional plan through one corner of the building taken on the line 4-4 in Fig. 2; Fig. 5 is a side elevation of a floor roller which may be used in carrying out my invention; Fig. 6 is a section of such floor roller taken on the line 6-6 in Fig. 5; Fig. 7 is a bottom plan of the container.

In Figs. 1 and 2, I have shown a building 10 having at least two floors 11 and 12 respectively for removable automobile body storage purposes. Within the building, preferably at one end thereof, I provide truck entrance bays 13, into which trucks with their bodies may be backed, as shown in Fig. 1. Suitable doors (not shown) may close the idle bays. A hoisting well extends above the truck bays for enabling a crane, indicated generally at 14, to raise a body from a motor truck positioned in any bay.

The crane is adapted to travel on the trackways 15 and 16 which are shown as supported by columns 17 and 18 respectively. This crane however, is mounted sufficiently above the well to permit a body to be raised to the height of at least the second floor, and one crane may function to permit the handling of containers for the entire building.

To facilitate the transfer of containers suspended from the crane 14, to the first floor, without necessitating the use of additional cranes extending at right angles to the crane 14, I have shown a carriage indicated at 20 which travels on tracks 21 and 22 respectively. The track 21 as illustrated, may be disposed beneath the level of the truck runway so as to permit trucks to enter the runway readily. The track 22 may be supported in any convenient position, and for this purpose I have illustrated brackets 23 on the columns 18. The carriage 20 is arranged to be moved lengthwise of the hoisting well. Thus a container may be raised by the crane from a truck body, then

transported, and deposited upon the carriage. The floor of the carriage is in the same plane as the surface of the floor 11, wherefore a container can be readily moved 5 from the carriage to the floor for storage purposes.

To facilitate the transference of containers which are supported by the crane to the second floor of the building, I have shown 10 a carriage 30 which may be mounted on tracks 31 and 32. These tracks also extend longitudinally of the hoisting well and are so positioned that the top surface of the carriage lies in the same plane as the surface 15 of the floor 12. The carriages 20 and 30 may be propelled by hand, or by any suitable mechanical power along their respective trackways.

To facilitate the transfer of containers between 20 the carriages and the respective floors, I prefer to employ rollers 40 which are rotatably mounted on the carriages and floors respectively. In the preferred form, these rollers are disposed beneath the surface of 25 the container support so that only a small portion of the tread projects thereabove. Moreover, these rollers preferably extend in parallel rows and in pairs so as to provide parallel lanes along which the containers 30 may be moved within the building.

Referring now to Figs. 5 and 6, I have shown each wheel as having a crowned or convex face 41, the edges of which are nearly tangent to the floor line, as shown in Figs. 5 35 and 6. Each wheel may be journaled on a shaft 42 on a roller bearing 43, while the shaft may be supported in a casing 44. As shown, the casing has a flat portion which is flush with the top of the floor and is adapted 40 to be secured thereto by screws 45. Thus only a small part of the wheel projects above the surface of the floor, thereby reducing the required overall clearance between the floor and ceiling to a minimum.

The container 52 which is usually a fabricated structure having a metal floor frame is provided on its under side adjacent the edges with longitudinal bars 53, troughed or concaved on their undersides as shown 50 in Fig. 6. Such container therefore may be readily guided by the rollers; the rollers however do not present any troublesome obstruction for hand trucking in spaces unoccupied by containers, nor do they injure the 55 rubber tires of hand trucks. The flat portions of the container floor bars at the sides of the concavities form a proper surface for supporting the container in an ordinary floor or support.

The movement of a container along a wheeled lane may be effected either by hand 60 or by mechanical means, such as a portable "industrial truck." Such a truck is also useful in shifting the carriage and the traveling crane by moving transversely of the build-

ing adjacent the crane well and drawing the carriage or crane by means of a rope leading diagonally thereto.

Assuming that a truck 50 has a removable body or container 52 positioned thereon and 70 that the container is to be transported to the first floor of the building, then the crane is stopped above the truck and the cables are brought into engagement with the container. Thereupon the container is lifted 75 from the truck and transported laterally, and then deposited on the rollers 40 of the carriage 20, from which it is rolled by hand or by any suitable mechanical power along the lane, before which the carriage is 80 stationed. The container is guided during such movement by the convexity of the wheels. The reverse procedure may be employed for transferring a container from any lane on the first floor to a truck standing in the 85 runway.

To transfer a container from a truck to a higher floor, the container is merely raised and the carriage is run laterally beneath it, or the container is transported and deposited 90 upon the carriage 30. Then while the container is being moved from the carriage to a lane in the second floor, the crane may be shifted to transfer another container to or from a truck.

A particular advantage of my invention is the fact that trucks may enter a building during the loading and unloading operation, thus leaving the space outside the building 100 clear for vehicular traffic and obviating the necessity for columns outside the building to support the crane trackway. A number of trucks may be backed into the building and receive or discharge their load in quick succession without waiting for the bodies 105 to be placed in their final position on the floors. If desired, a number of carriages may be mounted on each carriage trackway, wherefore the crane may be kept in use for loading and unloading purposes. This 110 facilitates the movement of the trucks between the stations.

In the ordinary operation of a storage building equipped with my transfer platform and lanes of rollers as described, care 115 is taken to store adjacent the far ends of the lanes those containers which will probably remain longest in storage and thus reduce the amount of internal shifting to remove a stored container from the building. By 120 leaving a lane normally unoccupied, or unoccupied space at the front of several lanes, it is a simple matter when any container is called for to run those in front thereof one after another onto the platform and transfer it to such idle lane or space until the deferred container is reached. In view of the fact that containers may remain where spotted for days at a time, the time lost in this internal shifting is a minor matter compared 125 130

with the advantages of cheapness and simplicity of hoisting and transferring equipment and the possibility of utilizing existing buildings in crowded business districts.

5 Having thus described my invention, I claim:—

1. The combination of a building having a crane well therein, a passageway from the exterior of the building whereby a truck 10 may be admitted to the well, a traveling crane traveling along the well and a platform movable horizontally along the well at a lower level than the crane and parallel with its movement, said platform being substantially on the same level as one of the floors of the building and being movable independently of the crane.

2. In combination, a building having enclosing walls, a truck passageway within 20 the building and adjacent one of the walls, a movable platform, a trackway therefor, a crane adapted to raise a removable body from a truck positioned in the passageway and to transport it and deposit it upon the 25 platform, said platform being operable in a direction parallel to movement of the crane independently of the crane.

3. In combination, a building having enclosing walls and a floor, the floor terminating short of one of the walls to provide a well and a truck runway within the building, a carriage movable along the runway at substantially the level of the floor, an overhead crane traveling along the runway 35 and adapted to raise a removable body positioned in the runway and to transport it and deposit it upon the carriage, and rotatable members mounted on the floor and arranged in lanes whereby a container may be transported from the carriage to the floor 40 without engaging the surface of the floor.

4. The combination of a building having a well therein, hoisting mechanism in the well, a platform movable along the well, said platform being substantially on the same level as one of the floors of the building, rollers carried by the platform and projecting above the top surface thereof, and rollers carried by the floor of the building.

50 5. The combination of a building having a crane well therein, a passageway from the exterior of the building whereby a truck may be admitted to the well, a traveling crane traveling along the well and a platform movable along the well at a lower level than the crane, said platform being substantially on the same level as one of the floors of the building, rollers some carried by the platform and some by the floor 55 of the building and projecting above the top surface thereof, the platform rollers being adapted to be brought into registration with the building rollers.

6. The combination of a building having 65 a well, a traveling crane supported on tracks

at the upper portion of the well, a platform supported on tracks in the well below the crane, said platform being adapted to register with one of the floors, and rollers in the floor arranged in a set of lanes at right angles to the well, whereby a removable truck body in the well beneath the crane may be lifted by the crane, deposited on the platform, caused to register with a selected lane, and roller along such lane. 70

7. In combination, a building having enclosing walls and having a floor terminating short of one of the walls to provide a truck runway, the wall adjacent the runway having entrances for trucks whereby trucks 80 may enter the building transversely of the runway, a carriage mounted to travel along the runway and substantially at the level of the floor, an overhead crane adapted to raise and transport a removable automobile body 85 from a truck positioned in the runway to the carriage, rollers mounted on the floor to provide spaced lanes, other rollers mounted on the carriage and adapted to be selectively aligned with the rollers in any of said lanes 90 upon movement of the carriage, whereby a removable automobile body may be transferred along the rollers from the carriage to one of said lanes.

8. The combination of a building having a well, a platform supported on tracks to travel in the well, said platform being adapted to register with one of the floors of the building, a passageway from the exterior of the building to said well, whereby a truck 100 with a removable body may enter the well, and crowned rollers in the floor of the building arranged in lanes each lane comprising two rows of rollers positioned to receive, support and guide such removable body. 105

9. The combination with a truck having a removable body, of a building having a well which they may enter, a movable platform in the well supported on a level with a floor of the building two rows of rollers carried by the platform projecting upwardly above the top thereof, and two corresponding rows of rollers carried by the floor, the body having base portions coacting with the rollers in a manner to guide the body. 110

10. The combination of a building having a well, a platform supported on tracks to travel in the well, said platform being adapted to register with one of the floors of the building, a removable body having at its base a pair of tread members of inverted trough shape and crowned rollers in the floor of the building adapted to coact with such tread members, said rollers being arranged in lanes, each lane comprising two rows of rollers positioned to receive, support and guide such removable body. 115

11. The combination with a truck having a removable body, of a building having a floor, two rows of crowned rollers carried by 120

the floor projecting upwardly above the top surface thereof, the removable body having two tread members of inverted trough shape in its base adapted to register with such 5 rows.

12. In combination, a building having a floor, parallel rows of crowned rollers mounted in the floor, and a removable automobile body having downwardly facing trough bars 10 in its base which may coact with said rollers.

13. The combination of a building having lanes of rollers in its floor, the rollers projecting slightly above the floor surface, means for raising a removable automobile 15 body and supporting it in position to register with such rollers, the body having on its underside suitable members to track on the rollers.

14. The combination of a building having 20 a floor with rows of rollers therein, the rollers projecting slightly above the floor sur-

face, a hoisting mechanism adapted to raise a removable automobile body from below the plane of the floor into a position above such plane, and a movable platform adapted to 25 support the body in position to be moved on said rollers.

15. The combination of a building having an elevated floor and a well at the end of the floor, a platform, tracks supporting the platform in such manner that it is movable along 30 the end of the floor, a hoisting mechanism adapted to raise a removable automobile body from below the floor into position above the platform and rollers mounted in 35 the floor and projecting slightly above the same and adapted to receive a body directly from the platform.

In testimony whereof, I hereunto affix my signature.

BENJAMIN F. FITCH.
